UNITED STATES PATENT OFFICE.

CHARLES D. LANNING, OF BOSTON, MASSACHUSETTS.

ELECTRICAL SYSTEM.

1,116,447.

Specification of Letters Patent. Patented Nov. 10, 1914.

Application filed December 30, 1905. Serial No. 293,973.

To all whom it may concern:

Be it known that I, CHARLES D. LANNING, a citizen of the United States, residing at Boston, in the county of Suffolk, State of Massachusetts, have invented an Improvement in Electrical Systems, of which the following description, in connection with the accompanying drawings, is a specification, like letters on the drawings representing like parts.

My invention consists in improvements in telephone systems and particularly in means for and methods of increasing the efficiency of production and transmission of voice-actuated currents.

Where a voice-actuated variable resistance is employed to vary the current flow therethrough, and to thereby produce electrical undulations corresponding to those of the voice, the intensity of such undulations for any given expenditure of voice energy, will ordinarily depend upon the strength of current flow through the variable resistance and where such resistance is diaphragm controlled, upon the excursion of the diaphragm or amplitude of vibration thereof resulting from such expenditure of voice energy. Increasing the intensity of current flowing through the variable resistance, and increasing the amplitude of diaphragm vibration, will within certain limits increase the intensity of electrical undulations, and therefore the efficiency of transformation of voice energy into electrical energy. It has been found, however, that the current flow cannot be increased beyond certain limits, without injury to the electrodes of the variable resistance, and this is particularly the case with the forms of carbon microphones in present commercial use. It is also well known that the diaphragm does not lend itself well to the reproduction of the complex and delicate voice vibrations, excepting as its natural period and amplitude of vibration are kept within certain limits and that any attempt to exceed these limits results in a distorted and inefficient voice reproduction even though it may be accompanied by a gain in intensity. It will be obvious that this is true, no matter whether such diaphragm is directly voice controlled, as in the case of an ordinary transmitter, or whether it is indirectly controlled through intermediate electro-magnetic devices, as in the case of a repeater.

My invention comprehends an arrangement of circuits in such way that the intensity of current flow whether a resistance or other transmitting medium is employed, may be maintained within proper limits; also such that when the transmitting medium is diaphragm controlled, that the diaphragms employed may be of suitable and usual proportions, yet the transformation of voice energy into electrical energy be accompanied by a marked gain in intensity.

My invention also comprehends means of general application for increasing the efficiency of producing and repeating telephone currents, also methods for more effective production and reproduction, as well as various instrumentalities for carrying these methods into effect.

My invention will be best understood by reference to the following description when taken in connection with the accompanying illustration of one specific embodiment thereof, while its scope will be more particularly pointed out in the appended claims.

Referring to the drawings,—Figure 1 shows diagrammatically the application of one form of my invention to a two-way repeater; Fig. 2, diagrammatically shows the same as applied to a one-way repeater; Fig. 3 shows a modification; Fig. 4 shows in plan one form of repeating instrument suitable for use in the system illustrated in Figs. 1 and 2; Fig. 5 shows the same in side elevation; Fig. 6 is a section on the line 6—6 in Fig. 4, looking toward the variable resistance; Fig. 7 is a plan view partially broken away and partially in section showing a different form of instrument; Fig. 8 is a section in elevation on the line 8—8, in Fig. 7, looking toward the variable resistance; Fig. 9 is a plan, partially broken away and partially in section, of a modified form of instrument; Fig. 10 shows still another form of repeater, and Fig. 11 shows a circuit arrangement employing the instrument illustrated in Fig. 10.

In the drawings, referring particularly to Fig. 1, and to the illustrated embodiment of my invention there shown, A and B are conventional representations of terminal telephone stations, adapted each to be used either as a sending or receiving station, and provided respectively with the transmitter, T, T', and the receivers R and R', connected.

as conventionally shown in usual manner to their respective line circuits, L and L' . In series with the line circuit, L , for example, as here assumed at an intermediate repeating station are the exciting or receiving coils, a, a', a^2 , wound upon suitable cores and adapted to control respectively the movements of the diaphragms, b, b' and b^2 , as the magnetism of the cores varies with the varying voice actuated currents over the said line circuit. Each of the said diaphragms is suitably connected to control through its movements a variable resistance c, c', c^2 , of any suitable construction connected each in a branch of the repeating circuit, d , in the main or common leg of which is the battery or other source of electromotive force e and the primary inducting coils, f and f' . The said parts a, b and c are intended as conventional illustrations of any form of variable resistance repeating device although herein I show the same as diaphragm controlled and electro-magnetically actuated. Inductively related to the primary f is the secondary coil g in the line circuit L , and inductively related to the primary f' , is the secondary g' , in the line circuit L' .

Suitably connected in the line circuit, L' , are the exciting coils, h, h', h^2 , corresponding to the coils a, a' and a^2 , in the line circuit L , and co-operating with said exciting coils are the diaphragms, i, i' and i^2 , and diaphragm controlled variable resistances k, k', k^2 , connected also in separate branches of the branched circuit d .

If it be assumed that A is the transmitting station any voice caused variation in the energy of the line circuit L varies the flux of the exciting coils and obviously causes the corresponding variation in each of the resistances c, c' and c^2 , and in the currents flowing through the respective branches of the branched circuit d , each branch circuit adding the effect of its current variations to the resultant current variation in the main repeating circuit d . The effect of these current variations is cumulatively transmitted through the primary relay coil, f' to the secondary coil g' in the line circuit L' and therethrough to the distant receiving station B, the said increased cumulative transmission of the several variable resistances being effected through the aid of currents of normal and moderate intensity flowing through the individual circuits of the respective resistances and, when, as in the illustrated system, such resistances are diaphragm-controlled through the aid of diaphragms which may be and preferably are of proportions best suited for efficient voice reproduction. In this particular form of repeater, the repeating effect is also further intensified by the action of the exciting coils, h, h', h^2 in the receiving line circuit L' . These coils are so connected that when ex-

cited by the transmission of the repeated impulses, they will act in harmony with the coils a, a' and a^2 , and cause variation in their respective resistances in the proper direction, to add also their cumulative effect upon the resultant resistance of circuit d to that of the resistances c, c' and c^2 , to thereby cause a further increased variation in the current flowing through circuit d .

The repeating or exciting coils for one station are preferably non-inductively related to the repeating coils for the other station, but nevertheless co-operate with such coils in cumulatively increasing the undulations in the common repeating circuit d .

The exciting or receiving coils may be connected in series with the line, as are the coils a, a' and a^2 , in the line L , or may be connected in multiple therewith, as are the coils, h, h', h^2 in the line L' .

It will be obvious that any voice produced energy variations transmitted from the station B will be repeated through the circuits described and the line L to the receiver at the station A in a manner similar to the transmission from the station A to the station B already described, the exciting coils h, h', h^2 , directly causing change in resistance of the circuit d and transmitting therefrom the resultant varying impulses to the circuit L through the primary coil f and the secondary g .

I may and herein do employ the condensers l and l' in series respectively with the line circuits L and L' and also the circuits m and n , the latter having the condenser o in series therewith, to link or join together the two circuits in the manner shown, thus providing a unified arrangement of circuits. I have also herein shown the two line circuits L and L' inductively related through the equi-valued induction coils p and p' .

It will be observed that the line circuits are connected by the variable resistances a, a', a^2, h, h', h^2 , the repeating induction coils p, p' and the direct circuits m, n . In this manner the character of the wave form is preserved to a maximum extent, inasmuch as it is conveyed directly through the circuits m, n . It is also conveyed through the repeating induction coils p, p' , and finally is conveyed through the said variable resistances.

Referring now to Fig. 2, I have shown therein a one-way repeater, the action of which will be obvious, in view of the foregoing explanation. The same is provided with a transmitter, T, connected to the sending circuit L , in usual manner, from which the undulations are repeated to the receiving circuit, L' , and the receiver, R, through the repeating circuit, d operatively related to the circuit L' , by means of the diaphragm controlled variable resistances c, c', c^2 , in

branches of the circuit d , and controlled by suitable magnets subject to excitation through the circuit L .

In Fig. 3 I have indicated another arrangement of circuits wherein the energy variations in a circuit L are communicated to a circuit L' , through the variations of a plurality of diaphragm controlled variable resistances, such resistances being not only individual but in separate and independent circuits, from which, however, the said energy variations are cumulatively transmitted to the circuit L' , by the inductive action of the primaries q and q' in the said variable resistance circuits upon the secondaries r and r' serially connected in the said line circuit L' .

It will be obvious that while I have described my invention with reference to a variable resistance and a diaphragm controlling the same actuated by the voice energy through the interposition of the electro-magnetic exciting means illustrated, the same is applicable to transmitting elements actuated directly by the voice energy without the interposition of any such devices, and to electro-magnetically actuated producing or reproducing elements controlled without the interposition of a diaphragm.

It will also be evident that while I have considered the current variation-producing factor to consist of a variable resistance, my invention in certain of its features is applicable to conditions where such variations are produced or reproduced by elements other than variable resistances.

Referring to Fig. 4, I have there shown a form of repeating instrument which is well adapted for effective use in the system described, although not limited in its application, and its mere use therein. This instrument has the three separate but adjacent magnets s , provided with exciting coils s' , adapted for connection either in multiple or series in the receiving circuit of the line. Each set of coils acts directly upon its cooperating armature s^2 , which is caused to vibrate a diaphragm-electrode structure forming a part of the variable resistance shown.

It is desirable to transmit the magnetic variations of the magnet to the repeating circuit with the least possible waste of effort, and the armature s^2 is therefore so associated with the magnet core as to provide a substantially complete magnetic circuit interrupted only as is necessary to obtain suitably vibratory armature movement.

The magnet is preferably initially excited and for this purpose while it desired separate exciting coils may be provided, herein the core is permanently magnetized to provide a light or low initial field permitting a low initial pull upon the armature and a

consequent reduction of the intervening air-gap without undue displacement of the controlling diaphragm in the resistance.

The magnetizing coils s' are placed at or near the extreme end of the magnet, so that their entire magnetizing power in the form of flux exterior to the magnet, is effective upon the armature with as little leakage as possible and with a circuit of minimum magnetic reluctance. The bobbins are vertically elongated, so that the pole pieces are brought closer together and the necessary width of the armature reduced. The magnet core is clamped in a horizontal position upon the supporting block, s^3 , by which it is delicately so adjustable to and from the armature or through any suitable means, such as the adjusting screw mechanism s^4 .

The maximum efficiency of the armature as a part of the metallic circuit of the magnet is secured by constructing it in block form, that is, designing it with a view to providing it with a path of suitably low magnetic reluctance as distinguished from a design for purposes of flexibility, such as is illustrated in the thin diaphragmatic armatures sometimes employed to perform the double function of magnetically co-operating with a magnet and positioning or controlling the vibratory electrode of the microphone.

The armature shown is in the form of a rectangular plate, preferably laminated to eliminate eddy current loss, and of a size sufficient to provide a suitable magnetic path for the magnetic flux of the receiving magnet, while at the same time providing an armature-electrode structure relatively light and of low inertia.

It will be seen that the armature working in the low initial field of the magnet has a normal position close to the poles thereof, and in intimate association with the magnet coils in a position to be most effectively influenced thereby. While of small mass and low inertia, it has sufficient metal to keep down the reluctance of the magnet circuit to the desired point, while its laminated structure further increases the magnetic efficiency of the device. The armature is required to perform no other function than to link the vibratory electrode directly and effectively to the magnet.

In the illustrated form of instrument there is provided a single casing t for the three sets of electrodes acting to retain a mass of interposed loose granular conducting material t' , such as carbon. This forms a compact instrument, while permitting the multiple connection of the variable resistances comprised by the several electrodes in the manner diagrammatically shown in Fig. 1.

The back electrode t^2 of each set is relatively fixed and supported upon a conducting plate t^3 , resting against an insulating

lining t^4 for the exterior back wall of the casing, and is connected to a binding post t^5 which projects exteriorly through an insulated bushing, whereby the electrode is effectively insulated from the casing of the instrument. The fixed electrode may be of any suitable material, such, for example, as hard polished carbon. In the illustrated form of instrument the vibratory electrode 10 and the controlling diaphragm therefor are united in a single composite structure consisting of the thin elastic disk t^6 of hard carbon, insulated from the casing and secured at its perimeter by the annular threaded nut t^7 . Obviously, if desired, the diaphragm may be formed of other substances, such as mica, and the electrode formed separately therefrom, but preferably the two whether formed separately or integrally are 20 arranged to constitute a composite diaphragm electrode-structure of relatively low weight and inertia and adapted to respond harmoniously and sensitively to the vibratory impulses of the armature.

25 The microphone casing is arranged directly to face the magnet, and preferably with each diaphragm coaxially aligned with the direction of magnetic pull. Each armature is directly and rigidly connected to the 30 vibratory electrode by means of a short and preferably light stem t^8 of aluminum or other suitable material. This stem forms a delicate reduced connection between the armature and the diaphragm electrode-structure, permitting the former to be constructed with sufficient area and mass for the best magnetic efficiency without impairing the vibratory capacity of the latter. The direct and rigid connection between the electrode and the armature provides an armature-electrode structure in one composite element having slight inertia and moving as a unit in direct response to the vibratory pull of the magnet.

45 The armature being attached centrally to the electrode-structure at the point of maximum movement thereof, the pull of the magnet comes directly on the diaphragm at its center and therefore upon the most sensitive and responsive part of the system. By 50 locating the microphone axially in line with the resultant pull of the magnet, the pull of the latter, the diaphragmatic pull and the movement of the electrode are all co-incident and act as coördinate factors to 55 transmit magnetic undulations directly to the electrode and make the latter delicately responsive thereto.

While it is ordinarily preferable to have 60 the vibratory electrodes of several coöperating variable resistances move with reference to relatively fixed or stationary electrodes, in order to obtain the full benefit of the "solid back" effect it may sometimes 65 be desirable where such resistances are used

in repeating instruments or for other purposes, to so arrange such vibratory electrodes that they act coöperatively with reference each to the other. In Fig. 7 I have shown an instrument having oppositely arranged but rectilinearly aligned receiving magnets, u and u' having coöperating armatures u^2 and u^3 , respectively. The armature u^2 is directly connected to the carbon diaphragm u^4 and the other armature to the 75 opposing coöperating diaphragm u^5 ; the two diaphragms being separated but conductively united by the interposed granular carbon u^6 loosely retained in the chamber of a stationary casing. The receiving magnets with their armatures are constructed upon the same magnetic considerations as those set forth in the description of the instrument shown in Fig. 4, and the connection of each armature to its respective diaphragm and the construction of the latter are also adequately described in connection with the foregoing instrument so as to require no further description here.

The receiving magnets are adapted for 80 connection in circuits constituting separate branches of the same line, as are the magnets h and h' in Fig. 1, or for inclusion in the separate line circuits of a two-way repeater as are the magnets a and a' in Fig. 1; 85 or for any other suitable purpose, but particularly where it is desired harmoniously to impress the cumulative effect of current undulations in two circuits upon a single circuit. The windings are preferably so 90 connected that attraction of one magnet upon its armature is accompanied by attraction of the other upon its armature, the cumulative effect of the two instruments being thereby transmitted to the variable resistance without, however, any unusual increase in the sensitiveness or size of each individual diaphragm.

In Fig. 9 there is shown an arrangement 95 of receiving magnets similar to that shown in Fig. 7 and a stationary resistance chamber v , the latter, however, being provided with a fixed or stationary partition wall v' supporting the stationary electrodes v^2 and v^3 , which coöperate with the vibratory diaphragm-electrodes v^4 and v^5 . This instrument gives the "solid back" effect of the stationary electrode.

In Fig. 10 I have shown an instrument 100 having receiving magnets and armatures similar to those illustrated in Figs. 7 and 9, the armatures, however, being rigidly connected to act upon the same vibratory electrode. For this purpose the casing w is provided with a stationary electrode w' and 105 the vibratory diaphragm-electrode w^2 . The latter has the light connecting stem w^3 , uniting it with the armature w^4 . The armature w^5 for the magnet has its stem rigidly 110 and directly connected to the stem w^3 by 115

the yoke or frame w^6 , which, in order to reduce its mass and momentum is preferably formed of some light material, such as thin sheet aluminum. The adjacent sides of the frame are twisted at right angles to give rigidity with compactness.

One application of the instrument is indicated in Fig. 11 where I have shown the same employed as a two-way repeater between the line circuits x and x' , the latter leading to two distant stations (not shown). In the supposed case there are two such instruments x^2 and x^3 employed, having their resistances connected in multiple for the reasons discussed in connection with the system shown in Fig. 1.

One side of the line is connected to energize a receiving magnet of each instrument; the connections being shown in series. The other side of the line is connected, herein serially, to energize the remaining magnets of the two instruments. The variations impressed by the receiving magnets upon their respective resistances are cumulatively impressed upon the common repeating circuit, x^4 , and thereby inductively impressed upon the line circuits. At the same time, the two line circuits, being mechanically linked, as it were, through the armature connections of their respective receiving magnets, have their current undulations forced more or less into harmony and have a diminished tendency to the re-actionary noise effects which repeated impulses ordinarily create upon the instrument which repeated them.

While for illustrative purposes I have shown and described one form of my invention, it is to be understood that the same is not limited to the details of parts or the relative arrangement of circuits here shown and disclosed, but that wide variations may be made from those illustrated, and that other applications and uses of the invention may be made without departing from the spirit of the invention.

Claims—

1. Telephone repeating means comprising a plurality of receiving magnets having each a co-operating armature and a variable resistance medium, the latter comprising fixed and movable electrodes with interposed granular conducting material, there being provided a single containing casing for the conducting material of said several resistances.

2. A variable resistance telephone instru-

ment comprising a single casing, a plurality of fixed electrodes within said casing, a diaphragm-electrode-structure co-operating with each of said fixed electrodes, and interposed granular conducting material between the several sets of electrodes and within said casing.

3. A variable resistance telephone instrument comprising a single casing, a plurality of fixed electrodes within said casing, a diaphragm-electrode-structure co-operating with each of said fixed electrodes, interposed granular conducting material between the several sets of electrodes and within said casing, an armature attached to each of said diaphragm-electrode-structures, and electromagnetic actuating means for each of said armatures.

4. A variable resistance telephone instrument having a plurality of relatively fixed electrodes, a movable diaphragm-electrode-structure co-operating with each of said fixed electrodes, and a body of electrically unseparated granular conducting material interposed between the electrodes, said several sets of electrodes being connected in individual circuits.

5. Telephone repeating means comprising a plurality of receiving magnets having each a co-operating armature and a resistance medium, the latter comprising fixed and movable electrodes with interposed conducting material, there being provided a single containing casing for the conducting material of said several resistances.

6. In a telephone system the combination with a line circuit, transmitting and receiving instruments at each end thereof, a telephone repeater comprising a variable resistance medium, a pair of coils in multiple connection controlling said variable resistance medium and in receiving relation to the transmitting device at one end, and a pair of similar coils in receiving relation to the transmitting instrument at the opposite end, said variable resistance medium being in transmitting relation to the receiving instrument at each end of the circuit.

In testimony whereof, I have signed my name to this specification, in the presence of two subscribing witnesses.

CHARLES D. LANNING.
